US00D576673S

(12) **United States Design Patent**
Petrie et al.

(10) **Patent No.:** **US D576,673 S**
(45) **Date of Patent:** **** Sep. 9, 2008**

(54) **BINDER**

(75) Inventors: **Aidan Petrie**, Jamestown, RI (US);
Marco Wo, Providence, RI (US); **Daniel Nelsen**, Providence, RI (US)
(73) Assignee: **Staples The Office Superstore LLC**,
Framingham, MA (US)
(**) Term: **14 Years**
(21) Appl. No.: **29/267,405**
(22) Filed: **Oct. 13, 2006**

(51) **LOC (8) Cl.** **19-04**

(52) **U.S. Cl.** **D19/26**

(58) **Field of Classification Search** D19/26-33,
D19/86; 206/232, 450, 472; 281/15.1, 39,
281/44-45, 19.1, 21.1, 22, 29, 31, 38; 283/63.1,
283/64; 402/4, 31, 73

See application file for complete search history.

(57) **CLAIM**

The ornamental design for a binder, as shown and described above.

DESCRIPTION

FIG. 1 is a perspective view of the binder, wherein the binder is in a closed configuration;

FIG. 2 is a front view of the embodiment of FIG. 1, wherein the binder is in an open configuration, the rear view being a mirror image thereof;

FIG. 3 is a right side view of the embodiment of FIG. 2, the left side view being a mirror image thereof;

FIG. 4 is a bottom view of the embodiment of FIG. 2, the top view being a mirror image thereof;

FIG. 5 is a perspective view of another embodiment of a binder, wherein the binder is in a closed configuration;

FIG. 6 is a front view of the embodiment of FIG. 5, wherein the binder is in an open configuration, the rear view being a mirror image thereof;

FIG. 7 is a right side view of the embodiment of FIG. 6, the left side view being a mirror image thereof, and,

FIG. 8 is a bottom view of the embodiment of FIG. 6, the top view being a mirror image thereof.

The broken lines are for illustrative purposes only and form no part of the claimed design.
